UNITED STATES PATENT OFFICE.

OLOF OHLSSON, OF SODERTELJE, SWEDEN.

INTERNAL-COMBUSTION ENGINE.

1,089,432.

Specification of Letters Patent. Patented Mar. 10, 1914.

Application filed May 22, 1907. Serial No. 375,069.

To all whom it may concern:

Be it known that I, OLOF OHLSSON, a subject of the King of Sweden, and resident of Sodertelje, Sweden, have invented certain 5 Improvements in Internal-Combustion Engines, of which the following is a specification.

In internal combustion engines, such as have been heretofore employed, the charge, 10 consisting of a suitable quantity of vaporized fuel such as petroleum, for example, or a combustible mixture of such vaporized fuel with air has ordinarily been directly introduced into the working cylinder in such a 15 manner that a very sudden and high pressure, similar to that of a heavy explosion results when the charge is ignited, which pressure operates as a violent blow upon the piston, while the same is at the termination 20 of its return stroke and before the commencement of its forward stroke. Under such circumstances, it is very difficult to effect the regulation desirable to meet varying requirements of power and irregular 25 running of the engine results, and as the inertia of the fly wheel cannot be overcome with sufficient rapidity a great strain is imposed upon the parts, nor can the high temperatures which result from the excessive 30 pressure developed at ignition of the charge be fully utilized and consequently a great part of the heat of the fuel is not converted into mechanical work but is lost.

An important object of the present invention 35 is to provide means whereby these disadvantages are avoided. This is attained by dividing the combustion period into two or more periods, the first one taking place in a special primary chamber and the other one 40 in a secondary chamber opened inward to the working or piston chamber and communicating with the primary chamber, the communication between the primary chamber and secondary chamber being valve controlled. The combustible gas or the fuel and 45 a quantity of air are introduced in the primary chamber and are mingled in the same and preliminarily ignited, a preliminary high pressure being thus effected in the same 50 during a combustion process which is only partial owing to the surplus of fuel in proportion to the air. The igniting operation is effected in the primary chamber when the 55 piston is at or near the outer reversing point, the ignition being dependent upon the compression or the pressure of the air previously

introduced in the working chamber which compression is effected by the piston. The valve controlling the communication between the primary chamber and secondary chamber is now opened at the pressure in the primary chamber and the ignited charge enters the secondary chamber. When meeting the compressed air in the secondary chamber, the combustion is completed. The 60 said completed combustion acts, like the ignition in the primary chamber, as an explosion but this explosion is however of a comparatively mild character owing to the fact that the compressed air has a comparatively greater volume with relation to the charge supplied through the valve for which volume there is room in the secondary chamber. The pressure now increases to or, more correctly, is fully maintained at the degree 65 70 which corresponds to the complete combustion so that the heat of the fuel is fully utilized. In addition to the increased effect already intimated advantage is attained by the said construction, that the explosion in 75 the secondary chamber is not effected until the piston has arrived at or near the reversing point on its upward or return stroke or, if this be necessary, until after the piston shall have commenced its downward or advanced stroke, and that if the volume of combustible fuel supplied to the engine is varied to meet the varying requirements of developed power, this will not interfere with the functions of ignition and combustion, the 80 85 complete combustion of the charge being assured irrespective of such variations within the limits of the air supply. Further it may be stated that an engine constructed in accordance with this embodiment of the invention works with great expansion and at a comparatively low pressure and moderately high temperature owing to which facts it is more durable than engines hitherto employed.

The invention consists in certain novel features of the construction, and combinations and arrangements of the several parts of the improved engine, whereby certain important advantages are attained, and the device is rendered simpler, less expensive and otherwise better adapted and more convenient for use, all as will be hereinafter fully set forth.

The novel features of the invention will 110 be carefully defined in the claims.

In order that my invention may be the

better understood, I will now proceed to describe the same with reference to the accompanying drawings, wherein—

Figure 1 is a vertical section of an engine constructed in accordance with an embodiment of my invention; Fig. 2 is a section on the line A—B of Fig. 1; Fig. 3 is a section of a part of the passage leading to the primary chamber and provided with an absorbent reservoir or retainer for the fuel; Fig. 4 is a section on the line C—D of Fig. 1; Fig. 5 illustrates the mixing device, which is located in the bottom part of the primary chamber and mixes the gas and air with each other; and Figs. 6, 7 and 8 illustrate further embodiments of my invention.

As herein shown the improved engine has the piston 2 which reciprocates in the cylinder or working chamber 1 and is connected with the crank 4 by means of the connecting rod 3, the same being as usual surrounded by a casing forming a compression chamber 5 in which vacuum and pressure are alternately produced by the piston. The primary chamber 6 is provided at the side of the cylinder. The upper end of the working chamber 1 is provided with a wide channel or secondary chamber 7 forming an extension thereof, and in communication with the primary chamber 6 but separated therefrom by the valve 8.

The valve 8 may be so arranged that it can be opened outward from the primary chamber 6 as shown in Figs. 1 and 6 or inward toward the said chamber as shown in Fig. 7, and is acted upon by a spring as shown in Fig. 1 or connected with a lever as shown in Figs. 6 and 7.

In the bottom or lower end of the primary chamber 6 is provided a mixer 9 shown on an enlarged scale in Fig. 5, and below the said mixer the chamber 6 communicates with the upper part of the working chamber 1 through a pipe or channel 10 which extends into the mixer and has a mouth 10^x directed downward. Exterior of the chamber 6 the said pipe or channel 10 is provided with a regulating valve 11. A channel 12 of greater diameter than the channel 10 leads from the bottom or lower end of the primary chamber 6 and communicates with the bottom or lower end of the working chamber 1 through an opening 14 and with the crank or compression chamber 5 through a branch pipe or channel 15. The channel 12 is separated from the chamber 6 by the valve 13 and the branch pipe or channel 15 is provided with a regulating valve 16, said valve 16 being under control of suitable governor mechanism (not shown). The channel 12 is arranged on a curve directed downwardly and the absorbent fuel retainer or reservoir 17 hereinbefore mentioned extends within the lower part of the same. The said absorbent fuel retainer or reservoir 17 consists

of a highly porous body acting like a strainer and produced by rolling up a fine brass-wire cloth or in any other suitable manner. The absorbent retainer or reservoir 17 communicates with a channel 18 leading from the fuel tank (not shown) and provided with a controlling valve 19 as is particularly shown in Fig. 3. A mixer is contained within the primary chamber 6 and consists of a plurality of disks 21 located one above the other and at some distance from each other. Each disk has two transverse passages 21^x provided on the same diameter and the passages of each two adjacent disks are set at angles of 90° with relation to each other, so that the passages 21^x are situated in staggered relation or zig-zag lines throughout the disk pile. The chamber 6 is also provided with an igniter which may be of any suitable construction, as for instance, it may consist of a tube 20 as shown in Fig. 1. The working chamber 1 communicates with the atmosphere through an opening 22 and the crank or compression chamber 5 communicates through a channel 25 with cavities or spaces 24 in the cylinder wall and cover, such cavities or spaces being provided with inlet openings 23 to the atmosphere.

The piston 2 acts, as usual, both as a working piston, *i. e.* is acted upon by the pressure of the expanding combustion gases and transmits the said pressure to the crank, and as a compressing piston for compressing the air in the cylinder 1 above the piston and in the crank chamber 5 alternately, said piston also creating a vacuum in the chamber last mentioned when moved upward. The pressure effected above the piston during the compression of the air is transmitted to the chamber 6 through the pipe or channel 10. The air compressed in the chamber 5 is used partly for blowing off the combustion products from the cylinder 1 above the piston when the latter is in its lowermost position and partly for causing the fuel to pass through the channel 12 to the mixer 9 in the chamber 6.

The engine works in two strokes and effects a compression at every stroke upward and is subjected to the pressure of combustion at every stroke downward. As the piston moves upwardly, vacuum is created in the compression or crank chamber 5 as hereinbefore stated, which vacuum is also effective in the channel 12 shut off by the closed valve 13 and by the piston covering the opening 14. Owing to this fact fuel is sucked into the retainer or reservoir 17 and as during the vacuum period no air current worth mentioning passes through the reservoir, the fuel remains the same. Consequently after the sucking operation has been effected the reservoir or retainer acts substantially like a moist sponge which can

easily give out the fuel to an air current passing through the channel 12. The quantity of petroleum to be sucked into the reservoir or retainer is controlled by adjusting the vacuum in the channel 15 which is effected by means of the valve 16 hereinbefore referred to as under control of suitable governor mechanism. Owing to the comparatively small quantity of fuel which is necessary for every working stroke a very small quantity of air may advantageously be led into the petroleum at the valve 19. This air, however, is not absolutely necessary. For this purpose a narrow passage 19^x is provided above the said valve 19 (Fig. 3) through which a small quantity of air may pass. As the piston is moved downwardly a pressure is created in the chamber 5 which as has been hereinbefore stated is effected also in the channel 12. The valve 19 provided in the conduit between the reservoir and the fuel tank, is then closed. As the piston is moved farther downward the opening 22 is uncovered while the opening 14 remains covered due to the fact that the opening 22 has a greater diameter vertically than the opening 14 and the lower side walls of said openings being on the same plane or level as is clearly shown in Fig. 1. When the chamber above the piston has been put into communication with the atmosphere, as has been described, the air in the channel 12 moves rapidly toward the chamber 6. This air causes the fuel in the reservoir 17 to pass with it and carries same past the valve 13 of the mechanism 9 which has been heated during the previous combustion period. During this operation the valve 13 in its opened or lifted position closes the mouth 10^x so that the charge cannot pass into the channel 10. As the piston is moved farther downward the opening 14 is uncovered. The greater part of the compressed air in the chamber 5 passes through the cylinder 4 to the atmosphere, the cylinder being thus freed from the products of combustion from the previous stroke and is filled with fresh air. As the air passes to the chamber 6 it carries the fuel with it from the beginning but owing to the greater weight of such fuel and the obstruction offered by the mixer the fuel is retarded in its movement. This causes the fuel to become divided which results in an effective mixing of the fuel and the air while the currents pass from and toward each other alternately in the spaces of the mixer and the openings, which continues during the movement upward of the fuel and the air, the fuel being at the same time heated and evaporated. This occurs even at the bottom of the mixer. The charge thus led into the mixer in filling the same possesses a preponderance of fuel owing to the fact that the reservoir or retainer 17 is located near the valve 13 and the compara-

tively narrow channel 12 does not permit the supply of any great quantity of air compared with the quantity of air necessary for the full combustion of the supplied fuel. As the piston turns back the pressure in the channel 12 is so reduced that the valve 13 closes. Owing to the fact that the mixer possesses greater heat at its upper part than at its lower part, the charge is gradually heated as it travels lengthwise of the mixer. This length of travel can be extended or shortened by making the disks or the spaces thicker or thinner and thus employ a greater number of disks or by making the openings 21^x wider or narrower and so on. The action of the mixer is dependent on the narrow shape of the spaces and on the position of the openings in staggered relation or zig-zag lines, in consequence whereof the air and the fuel are divided into currents which cross and pass each other continuously. As the piston is moved upwardly the air in the piston chamber and the primary chamber which is in communication with the piston chamber through the channel 10, is compressed more and more. However, the pressure in the chamber 6 does not increase with the same rapidity as in the piston chamber and the secondary chamber 7 due to the resistance exerted by the pipe 10 which resistance can be increased or decreased by means of the valve 11. Consequently, it is possible to cause the pressure in the chamber 6 to reach its maximum only when the piston has been reversed. The fact is that the pressure in the chamber no doubt can be increased though the piston has been reversed for though the movement downward of the piston causes a reduction of the pressure provided there is nothing causing an addition to the pressure, the pressure above the piston is great enough as long as the piston is in the vicinity of the reversing point to cause the air to continue in its movement to the chamber 6 until pressure is the same in both chambers. Owing to this fact it is possible to regulate the pressure in the primary chamber and to fix the position of the crank at the moment when the pressure in the chamber has reached its maximum so that the piston has already been reversed and has passed downward, a greater or shorter distance which facts are of great importance for the operation of the engine. The maximum pressure in the chamber 6 effects the ignition of the charge in the same. However, the said ignition is dependent not only on the pressure but also on the proportions of air and gas, consequently in the present case it is presumed that the said proportion (the normal mixture) is the proper one in order that the presence of the other factor (the proper pressure) may be sufficient for effecting the ignition. The said proportion of the air and gas may be 130

easily controlled partly by means of the valve 11 and partly by means of the valve 16 and also by means of any adjustable valve or equivalent provided in the fuel channel.

5 From what is stated above it appears that by increasing or decreasing the air supply to the chamber 6 by means of the valve 11 ignition may be effected on any desired crank 10 position in the vicinity of the dead point or near the same and also after the crank has passed the said point and is being moved downward. Air is forced into the chamber 6 substantially at the end of the compression 15 period, as the pressure then increases rapidly. The said air forces the gas mixture upward in the chamber 6 and dilutes the same to such a degree that the bottom part of the chamber is filled with the normal mixture 20 while the top part of the chamber is still filled with a mixture in which there is a great surplus of fuel. Consequently an ignition or primary explosion takes place in the chamber 6 as the piston is at or near the upper reversing point. This primary 25 explosion cannot be more violent than permitted by the air forced into the chamber through the pipe 10 and takes place in the bottom part of the chamber only. The gas mixture 30 in the top part of the chamber cannot burn owing to the lack of air but it is heated to a great extent. The valve 8 is opened by the increased pressure and the mixture is forced from the chamber 6 into 35 the chamber 7 in which it is brought in contact with the compressed air. Here the second and complete explosion takes place and the fuel of the mixture burns up completely. During the said operation the pressure is 40 not increased much but on the other hand it remains at a substantially constant degree for a longer part of the piston stroke owing partly to the fact that the combustion takes place successively according as the fuel and 45 the air have time to come in contact with each other in the same extended channel of the secondary chamber 7; and partly to the expansion of the comparatively great quantity of air in the secondary chamber 7. The 50 fact is that the secondary chamber 7 has such a capacity that the quantity of air held by the same considerably exceeds the quantity necessary for the combustion of the charge. As the piston is near the lower reversing 55 point the combustion gases escape through the opening 22 with a very low pressure and a low temperature. Therefore the pressure originally effected in the chamber 6 partly by the piston and partly in the ignition is 60 now consumed.

The engine may be so constructed that the secondary chamber 7 forms a part of the piston chamber proper. The channel 10 may be provided with a valve 11^x closing 65 the same in a direction from the chamber 6

(Fig. 7). As the channel 12 extends downward in a curve fuel which possibly drops from the reservoir or channel 17 will gather on the bottom of the channel and is carried with the air when forced into the chamber 70 in the succeeding operation.

The construction illustrated in Fig. 7 differs from the construction shown in Fig. 1 in the period between the first and second explosions being not left to itself but made 75 dependent on the motion of the engine. The said period can be lengthened or shortened owing to the velocity of the engine, the fuel quantity, the load of the engine and so on. The pipe 10 is somewhat larger than in Fig. 80 1 so that the compressed air can enter the bottom part of the chamber 6 more easily and rapidly or, in other words, so that the pressure in the chamber 6 increases with substantially the same rapidity as in the 85 secondary chamber 7. During the compression period as soon as such a quantity of air has entered the bottom part of the chamber 6 as is necessary to attain a certain inflammability or rapid inflammability of the 90 mixture in the same to form the required mixture, the first explosion takes place. At the same moment, the pressure in the chamber 6 increases and the valve 8 is shut so that communication with the piston chamber 95 is interrupted. Consequently, the said first explosion may take place at any position of the piston without any retarding action on the movement outward of the piston. The pressure in the chamber 6 is stored, so 100 to say, owing to which fact more time is gained for the heating of the gas in the top part of the chamber until the moment when the piston passes the reversing point, or immediately afterward when the valve 8 is 105 opened mechanically and the charge enters the secondary chamber 7 and is completely burnt therein. The valve 8 is operated by any suitable means to keep it in open position and is held in closed position by a 110 spring or the like during the compression period.

In the form shown in Fig. 8 two relatively parallel primary chambers are employed. The construction of the same need not be 115 especially explained. The said chambers may act either simultaneously or alternately and in the latter case admitting the charge into the secondary chamber 7 alternately. In this embodiment of the invention two 120 compressing chambers may be used.

It may here be stated that careful examinations have shown that the gas mixture heated during the preliminary ignition is extremely inflammable in consequence 125 whereof the secondary combustion is very complete. There is a great advantage in having the temperature in the chamber 6 always the same or substantially the same independently of the work of the engine 130

which is due to the fixed limit of the combustion operation in the said chamber. Therefore the change of the temperature in the working chamber caused by the combustion in the secondary chamber 7 and the movement of the piston can have no disturbing effect upon the preliminary ignition of the first combustion. This assures the engine working in a reliable manner even under the most varying conditions.

When the piston has been moved upwardly a sufficient distance to uncover the channel 25 the atmospheric air entering through the opening 23 passes through the spaces 24 in the cylinder wall and through the channel 25 into the crank chamber in which a partial vacuum has been created during the movement of the piston. In this manner refrigeration of the working cylinder by means of air is effected in the cylinder wall and by means of the air entering the chamber 5 the heat is saved which is otherwise lost by radiation.

The ignition tube 20 hereinbefore referred to is used only at the starting of the engine or during cold weather when the external air may unduly chill the parts.

As already stated the engine may be so arranged that it opens the valve 8 by means of a cam acting on a lever or the like connected with the valve either outwardly (Fig. 6) or inwardly against the resistance of a spring (Fig. 7).

In addition to the described mode of action characteristic of the engine the simplicity and durability of the engine in comparison with those hitherto used may be pointed out.

The sound damper, as well as the water cooling device can be dispensed with owing to the low pressure and the moderately high temperature, as also may all extra devices hitherto used for the cooling and lubrication of the piston, all parts of the engine being subject to a less violent strain.

From the above description it will be seen that the improved internal combustion engine constructed in accordance with my invention, is of an extremely simple and comparatively inexpensive nature and is particularly well adapted for use by reason of its strength and convenience of operation and it will also be obvious from the above description that the device is susceptible of considerable modification without material departure from the principles and spirit of the invention and for this reason I do not desire to be understood as limiting myself to the precise form and arrangement of the several parts, as herein set forth in carrying out my invention in practice. For instance, a plurality of cylinders and primary chambers may be provided and the reservoir as well as the mixer may also be modified in several ways. It may also be pointed out

that the dimensions of the cylinder 1 with relation to the primary chamber 6 and the secondary chamber 7 respectively, may be varied and also the degree of compression dependent upon the desired degree of expansion.

Having thus described my invention, what I claim as new and desire to secure by Letters Patent is:

1. An internal combustion engine having a cylinder, a piston movable therein, a primary chamber having unyielding walls, means for admitting a combustible charge to the primary chamber, and means for admitting air to the primary chamber, said piston being adapted for successive operation first to supply a combustible charge to the primary chamber and afterward to supply air thereto to increase the pressure therein, a secondary chamber adapted to afford communication from the primary chamber to the cylinder of the engine, means for admitting a supply of air to the cylinder, means to close communication between the primary chamber and the secondary chamber during compression of the charge in the primary chamber, and means operable upon the compression stroke of the piston for igniting the combustible charge in the primary chamber whereby the same is caused to be discharged into the secondary chamber and mingled with the air therein contained.

2. An internal combustion engine having a cylinder, a piston movable therein, a primary chamber having unyielding walls, means for admitting a combustible charge to the primary chamber, means for admitting air to the primary chamber, said piston being adapted for successive operation to supply a fuel charge to said primary chamber and afterward to supply air thereto, increasing the pressure therein, a secondary chamber adapted to afford communication between the primary chamber and the cylinder of the engine, means for admitting air to the cylinder, a valve controlling communication between the primary chamber and the secondary chamber and adapted to remain normally in closed position, and means operable upon the compression stroke of the piston for igniting the combustible charge in the primary chamber whereby the same is caused to be discharged into the secondary chamber and mingled with the air therein contained.

3. An internal combustion engine having a cylinder, a piston movable therein, a primary chamber, a secondary chamber affording communication from the primary chamber to the cylinder, means for controlling communication from the primary chamber to the secondary chamber, a mixing member extended in the primary chamber, means for supplying a combustible charge to the

mixing member, means for directing a supply of air along the mixing member for admixture with the combustible charge, and means operable upon the compression stroke of the piston for igniting the charge in the primary chamber to cause the same to be discharged into the secondary chamber and mingled with the air therein contained.

4. An internal combustion engine having a cylinder, a piston movable therein, a primary chamber, a secondary chamber affording communication from the primary chamber to the cylinder, means for admitting a supply of air to the cylinder, means for controlling communication from the primary chamber to the secondary chamber, means for admitting a combustible charge to the primary chamber, a mixing member in the primary chamber, and means for supplying a current of air from the cylinder to the mixing member in a direction to force the combustible charge through the mixing member toward the secondary chamber.

5. An internal combustion engine having a cylinder, a piston movable therein, a primary chamber, a secondary chamber affording communication from the primary chamber to the cylinder, a compression chamber, means for admitting air to the cylinder, a passage affording communication between the primary chamber and the cylinder, a second passage affording communication between the primary chamber and the compression chamber, means for supplying fuel within the said second named passage, said piston being capable of operation first to draw fuel into the said second named passage and afterward to increase the tension of air in the compression chamber whereby the same is forced through the second passage into the primary chamber, and means for igniting the charge in the primary chamber.

6. An internal combustion engine having a cylinder, a primary chamber, a secondary chamber affording communication from the primary chamber to the cylinder, a rear compression chamber adapted to contain a supply of air, means for admitting a supply of air thereto, means for admitting air to the cylinder, a fuel supply passage affording communication from the rear compression chamber to the primary chamber, means for supplying fuel to said passage, a piston in the cylinder and adapted, when moved in one direction, to lower the air pressure, in the compression chamber whereby fuel is drawn into said passage and when moved in the reverse direction to increase the pressure in said compression chamber, whereby said fuel is forced from said passage into the primary chamber and means for igniting the charge in said primary chamber.

7. An internal combustion engine having a cylinder, a primary chamber, a secondary

chamber affording communication from the primary chamber to the cylinder, means for admitting a supply of air to the cylinder, a fuel supply passage adapted for communication with the primary chamber, means for supplying fuel to said passage and comprising a fuel supply pipe and a porous fuel reservoir located in such passage and adapted to receive fuel from said supply pipe and means including a piston operable in the cylinder capable of operation first to draw fuel from said fuel supply pipe into said porous reservoir and afterward to force air through such passage to vaporize the fuel carried by the reservoir and convey the same into the primary chamber, and means for igniting the charge in the primary chamber.

8. An internal combustion engine having a cylinder, a primary chamber, a secondary chamber affording communication between the primary chamber and the cylinder, means for admitting a supply of air to the cylinder, a passage affording communication between the primary chamber and the cylinder and being arranged on a downwardly directed curve, a compression chamber, a second passage affording communication between the primary chamber and the compression chamber, means for supplying fuel to said second named passage and comprising a fuel supply pipe and a porous fuel reservoir located within the curved portion of the passage and adapted to receive fuel from said pipe, a piston movable in the cylinder capable of operation, first to draw fuel from the supply pipe into said reservoir and afterward to force air through the second passage into the primary chamber, and means for igniting the charge in the primary chamber.

9. An internal combustion engine having a cylinder, a primary chamber, a secondary chamber affording communication between the primary chamber and the cylinder, a compression chamber, means for admitting a supply of air to the cylinder, a passage affording communication between the primary chamber and the cylinder, a valve controlling said passage, a second passage affording communication between the primary chamber and the compression chamber, means for supplying fuel within the second named passage, means including a piston movable in the cylinder and capable of operation, first to draw fuel into the second named passage and afterward to increase the tension of air in the compression chamber whereby the same is forced through the second passage into the primary chamber, and means for igniting the charge in the primary chamber.

10. An internal combustion engine having a cylinder, a primary chamber, fuel supplying means therefor, a secondary chamber affording communication from the primary

chamber to the cylinder, means for admitting a supply of air to the cylinder, a rear compression chamber, ducts formed in the cylinder wall and forming an air inlet for the compression chamber, a passage affording communication from the compression chamber to the primary chamber, a piston in the cylinder arranged to increase the tension of the air in the compression chamber where-
5 by the same is forced through said passage into the primary chamber, and means for igniting the charge in the primary chamber.

10 11. An internal combustion engine having a cylinder, a primary chamber, a secondary chamber affording communication from the primary chamber to the cylinder, means for admitting a supply of air to the cylinder, a rear compression chamber, a passage affording communication from the rear compres-
15 sion chamber to the primary chamber, means for supplying fuel to said passage, a piston
20

in the cylinder and adapted when moved in one direction to lower the air pressure in the rear compression chamber, and when moved in the reverse direction to increase the air 25 pressure in said compression chamber whereby air is forced therefrom through such passage to force fuel therefrom into the primary chamber, a duct formed in the cylinder wall and affording an air inlet to the compression chamber when the piston is moved to lower the air pressure in such chamber, said duct being closed during the reverse stroke of the piston to prevent back flow of air from the compression chamber. 30 35

In witness whereof, I have hereunto signed my name in the presence of two sub-
scribing witnesses.
